UNITED STATES PATENT OFFICE

2,111,237

FIRE ALARM SIGNALING SYSTEM

Paul G. Brack, Somerville, Mass.

Application April 17, 1937, Serial No. 137,491

2 Claims. (Cl. 177—383)

In the fire fighting systems generally employed in the cities of this country, each fire company services a definite territory in which a certain number of alarm boxes are located. When a given company responds to an alarm of fire that comes in from a certain alarm box, another company, usually in adjacent territory, has assigned to it the servicing of the other alarm boxes, which otherwise are covered by the company first mentioned.

When a given fire company responds to a still alarm, the companies at the other stations are notified either by telephone, or a signaling system, that the company first named is out of service, and in such case, the chief of one of the remaining companies by consulting his running cards or other records ascertains that until the return of the company out on duty, his own company must respond to alarms sent in from the territory covered by the company that is now out, as well as to alarms within his own territory. Upon the return of the company to its station, the remaining companies are notified by telephone or otherwise, and thereupon, that one of said companies whose duty it was to service the territory normally covered by the company first mentioned is relieved of further responsibility for responding to alarms from any except those sent in from its own territory. Considerable confusion frequently results from the system above briefly outlined and much time in responding to an alarm is lost, especially where two or more companies are out at the same time.

The object of the present invention is to provide a signaling system whereby the telephone and still alarm system employed to notify each company of the movements of the other, and the confusion and loss of time resulting therefrom, are eliminated.

By means of the present invention, an officer of each company which responds to an alarm of fire actuates a circuit closer, thereby energizing visual signals at each of the other stations indicating that his own company is out, and simultaneously therewith energizing at one of the other stations visual signals indicating that such other company must service the call boxes in the territory of the company first mentioned until the return of the latter. Upon the return of the company responding to the alarm, the said circuit closer is again actuated to open the circuit previously closed thereby, whereupon the indicating devices above mentioned are de-energized.

Specifically, if station No. 1 covers alarm boxes A, B and C, station No. 2, boxes D, E and F, sta-

tion No. 3, boxes G, H, and I, and station No. 4, boxes J, K, and L; when the company of station No. 1 responds to an alarm from box A, for example, the closing of a switch at station 1 will light lamps at all the stations which will illuminate panels each bearing the number 1, and at station No. 2 will illuminate panels marked, respectively, A, B, C. Each company by means of the illuminated panels is notified that company No. 1 is out on duty, and station No. 2 is informed by the call-box-indicating lights that should an alarm be sounded from any call box within the territory covered by company No. 1, it will be its duty to service such call until the return of company No. 1.

In like manner, if company No. 2 is responding to an alarm, the figure 2 is illuminated on panels at all of the stations and at station No. 3 there will appear on illuminated panels, the letters D, E, F (in the present instance) informing company No. 3 that until the return of company No. 2 it will be the duty of company No. 3 to service all alarms sounded by the boxes identified, for the purpose of this example, as D, E, and F, etc.

In the drawings accompanying and forming a part of this specification, Figure 1 is an electrical diagram embodying my invention.

Fig. 2 is a front elevation of a cabinet that may be employed in connection with my system.

Fig. 3 is a vertical section taken on the line 3—3 of Fig. 2.

Fig. 4 is a horizontal section taken on the line 4—4 of Fig. 2.

In the particular drawing selected for more fully disclosing the principle of my invention, a schematic representation of circuits applicable to the fire fighting system of a small town having four engine companies is shown. At each engine house is placed a cabinet 10 divided longitudinally by the partitions 11 into four compartments 12, 13, 14, 15, and the compartment 12 is divided transversely by the partitions 16 into four compartments 17, 18, 19, 20. In each of said compartments is placed an electric lamp, and a transparent panel closes the front thereof. The panel 21 bears the numbers 1, 2, 3 and 4, indicating the fire stations of the system, and each of the three sets of panels 22, 23, 24, carry the numbers indicating the call boxes placed in different parts of the town. In each of the compartments 16 is placed a lamp 25 for illuminating the panel 21 and the fire station indicia carried thereby, and in each of the compartments 12, 13, 14 and 15 is lamp 26 to illuminate the panels 22, 23, 24 carrying the call box indicia.

It is to be understood, of course, that my invention is not limited to the number of fire stations employed in the system and that the cabinet aforesaid will be divided into the requisite number of compartments, depending upon the extent of the town's equipment. It will be understood, also, that my invention is applicable to ladder as well as to engine companies.

- 5   30, 31, indicate a power circuit, and the conductors 32, 33, 34, and 35 are conductors included in the same cable with the conductors 30 and 31. By the switches or circuit closers 36, 37, 38, 39, the various signal indicating devices at the respective fire stations are controlled. Thus 10
- 15   when the switch 36 is closed at station No. 1, there will be a circuit through the fire-station-indicating lamps 1 at each of the four stations, thereby indicating to the companies 2, 3, and 4 that company No. 1 has responded to an alarm of fire sent 15
- 20   from a call box located within the territory covered by station No. 1. In this particular instance, it is assumed that there are three such call boxes which, for convenience of illustration, are designated A, B and C. The closure of switch 36 in 20
- 25   addition to lighting lamps 1 at each of the four stations, will also light the lamps A, B, C, at station No. 2, (that is to say, the lamps in the compartment 22, the transparent panels closing the same bearing the letters A, B and C), thereby 25
- 30   informing engine company No. 2 that company No. 1 has responded to an alarm sent in from alarm box A, or B, or C, and that until said company No. 1 returns, station No. 2 is responsible for alarms sent in from the other call boxes normally serviced by company No. 1. In like manner, when switch 37 is closed, the lights 19 in each cabinet at all four stations are energized and the information conveyed to companies Nos. 1, 3, 30
- 35   and 4 that company No. 2 has responded to an 35
- 40   alarm sent in from a box in its territory.

The closure of switch 37 at station No. 2 causes the lighting of the lamps D, E, F, at station No. 3 and until the return of company No. 2, station No. 3 is responsible for all alarms sent in from 45

45   call boxes D, E, or F.

When the switch 38 at station No. 3 is closed, the lamps 19 in each cabinet are lighted, causing the transparent panels bearing the number 3 to be illuminated, and in addition, the lamps behind 50

50   the panels bearing the letters G, H, I, at station No. 4, showing that until the return of company No. 3, station No. 4 is responsible for all alarms sent in from call boxes G, H, I.

Upon the closure of switch 39 at station No. 4, 55

55   the lamps 20 in each cabinet are lighted, each company thereby is informed that company No. 4 is out, and in addition, company No. 1, by the

lighting of the lamps behind the panels bearing the letters J, K, L, at station No. 1, is informed that it must respond to all alarms from boxes J, K, L, until the return of company No. 4.

Upon the return of a company to its station 5 house, the switch which was thrown to close the circuit upon the departure of the company is opened, thereby extinguishing the fire-station-indicating lights 1, 2, 3, or 4, as the case may be, and informing the company at whose station the 10 call-box-indicating lamps were lighted upon the closure of said switch that its responsibility for calls originating from the other station's territory has ceased.

It will be clear that by means of my invention, 15 each company is definitely apprised as to the movements of the others and all uncertainty as to the obligations and responsibilities of the respective companies for the servicing of the alarm boxes in the territory of a company out on duty 20 are removed.

Having thus described an illustrative embodiment of my invention, without however limiting the same, either to the mechanical or the electrical features thereof, what I claim and desire 25 to secure by Letters Patent is:

1. In a fire-alarm signaling system, a plurality of sets of fire-station-indicating devices, each set being located at each of a number of fire stations and each indicating-device of each set being indicative of one station only, a source of electrical energy, circuits interconnecting said fire-station-indicating devices, switch means at each said station for connecting said source to each device at each station indicative of the station at which 30 the actuated switch is located, a plurality of sets of call-box-indicating devices, each indicative of the call-boxes covered by one of said fire stations only, and means connecting each set of call-box-indicating devices for actuation simultaneously 40 with a fire-station-indicating device at a station other than that at which said switch means is located.

2. In a fire alarm signaling system, two fire-station-indicating devices, each located at a fire 45 station and both indicative of one fire station only, a source of electrical energy, circuits interconnecting said fire-station-indicating devices, switch means at the first fire station for simultaneously actuating said devices at both stations, 50 a set of call-box-indicating devices at the second fire station indicative of the call-boxes covered by the first of said stations, and means connecting said call-box-indicating devices for simultaneous actuation with the fire-station-indicating 55 device at said second station.

PAUL G. BRACK.
